UNITED STATES PATENT OFFICE

HILMER F. RODLER, OF DAVENPORT, IOWA, ASSIGNOR TO CALVIN J. MUMMERT, OF
WEST NEW YORK, NEW JERSEY

LIQUID-FUEL HEATING APPARATUS

Application filed April 23, 1925. Serial No. 25,348.

My present invention relates to means for preparing liquid fuel, more especially oil, for burning and mixing the prepared fuel with the proper amount of air for combustion. Among the objects of my invention are to produce an improved liquid fuel burner; to produce a liquid fuel burner which will function automatically and without failure; to produce an improved device for converting liquid fuel into a combustible mixture; to improve upon the means for supplying fuel to the means for mechanically breaking it up; to provide improved means for timing the control valves in a mechanism of the character described; to improve upon prior valve construction; to improve upon the means for mixing air with the fuel; to provide means for preventing dirt from accumulating upon the oil nebulizing means; to produce an oil burning heater which can be adjusted for different sized furnaces by the exchange of a minimum number of parts; to provide an improved method of producing a combustible gas; to improve upon the method of igniting the fuel in a liquid fuel burner; to improve upon the mode of adjusting the amount of air admitted to the burning chamber, and such further objects, advantages and capabilities as will hereafter more fully appear and as are inherent in the mechanism disclosed.

My invention further resides in the combination, construction and arrangement of parts illustrated in the accompanying drawings and, while I have shown therein a preferred embodiment of said invention, I desire the same to be understood as illustrative only and not as limiting my invention.

In the drawings annexed hereto and forming a part hereof, Fig. 1 is a plan view of my improved apparatus; Fig. 2 is a transverse section between the motors, pump and controlling valves substantially along the plane indicated by the line 2-2, Fig. 1; Fig. 3 is a vertical section through a combustion chamber, showing my improved burner in elevation; Fig. 4 is a vertical longitudinal section through the burner head and its immediate driving mechanism;

Fig. 5 is an enlarged fragmentary section through the burner head; Fig. 6 is a fragmentary elevation of the valve mechanism and the actuating motor therefor; Fig. 7 is an elevation of one of the valves; Fig. 8 is an elevation of a valve body at a right angle to the elevation shown in Fig. 7; Fig. 9 is an expanded view of a valve core and the parts associated therewith; Fig. 9^a is a transverse section through Fig. 9 substantially along the plane indicated by the line 9^a-9^a; Fig. 10 is an elevation of the part shown at the right in Fig. 9 designed to show how adjustment between the valves is secured; Fig. 11 is a plan view of the casting which supports the lining of the fire box; Fig. 12 is an elevation of means whereby adjustment of the draft regulator is secured; Fig. 13 is an elevation at a right angle to Fig. 12; Fig. 14 is a fragmentary section through the igniting means shown at the right in Fig. 3, with the parts in a somewhat different position; and Fig. 15 is an incomplete plan view, Fig. 16 an edge view and Fig. 17 an inner face elevation of a fire brick used in building the fire box for a furnace in which my oil burner is used.

Referring more in detail to the annexed drawings, a base 1 is provided with legs 2 whereby it may be secured in place. This base carries an actuating motor 3, a driving motor 4, a burner assembly 5, electrical high tension mechanism 6, manual regulating valves 7 and 8, automatic cut-off valves 9 and 10 and a pump 11.

The shaft 12 of the motor 4 is connected by means of a flexible coupling 13 with the rotor of the pump 11 and this is in turn connected by a flexible coupling 14 with the shaft 15 which has mounted thereon a bevel gear 16 (shown in Fig. 4). This bevel gear 16 meshes with a corresponding gear 17 secured to the vertical shaft 18. These gears are mounted in the gear casing 19 which has secured to its upper end a bearing casing 20. Secured in the lower part of the gear casing 19 is an adjustable thrust bearing element 21 which may be adjusted by loosening the set nut 22 and then turning the element 101

21 until the gears 16 and 17 mesh properly. The nut 22 is then tightened to place to hold element 21 in its adjusted position.

5 A well in the bottom of element 21 carries a ball 23 upon which rests a hardened steel pin 24 to serve as a substantially frictionless thrust bearing for the shaft 18. The lower end 25 of said shaft is held from lateral play by an appropriate anti-friction bearing 26 mounted in the upper end of element 21. A similar anti-friction bearing 27 laterally supports the central portion of the shaft 18 where it passes through the bottom of the bearing casing 20. Another anti-friction bearing laterally supports the upper portion of the shaft 18 and is mounted in diaphragm 29 which divides the bearing casing into upper and lower chambers. A gland 30 is applied to the lower part of the 10 diaphragm 29 to make a tight joint between the shaft and the diaphragm, in order to substantially prevent the escape of oil from oil chamber 31 in the upper part of the bearing housing. A similar gland 32 prevents the escape of oil around the shaft at 15 the top of the casing 20. A nipple 33 is attached to or integral with the wall of the chamber 31 so that an oil delivery pipe may be connected thereto for the delivery of fuel 20 to the said chamber.

The shaft 18 has a longitudinal aperture 34 extending from its upper end downwardly to the central part of chamber 31 and has a lateral opening 35 connecting the 25 longitudinal aperture with the chamber 31. The upper end of the shaft is screw-threaded at 36 for the reception of the nebulizer head 37. The extreme upper end of the shaft 30 is provided with a pair of channels 38 leading from the upper extremity backwardly so that oil rising through channel 34 and overflowing on the upper end of the shaft will pass downwardly through the grooves 38 into the cup 39 in the upper surface of 40 the nebulizer head 37. A guard and air vane carrier plate 40 having an internally screw-threaded boss 41 is screwed on to the upper end of the shaft 18. This is provided with a plurality of openings 42 between its 45 middle and periphery for the entry of air therethrough into the space between the plate 40 and a dished plate 43 of the nebulizer head. A plurality of air vanes 44 are carried by the underside of the plate 40 near 50 the outer periphery thereof to throw air outwardly toward a furnace wall when the shaft 18 is rotated. The direction of the threading on the upper end of the shaft will be dependent upon the direction of rotation 55 of the shaft, and should be such that the driving of the shaft by the gearing 16, 17 will have a tendency to tighten the head 37 and the plate 40 upon the shaft.

The periphery of the dished plate 43 is 60 ground concave as shown at 45 to form at

the upper side of the plate a feather edge 46 from which the fuel will be thrown off in a very finely divided state, such as results from the operation of a nebulizer. This is therefore called a nebulizer element. Air 70 vanes 47 are preferably integrally formed with the underside of the plate 43 and extend downwardly along the side of the hub of this element, as shown most clearly in Figs. 4 and 5. These vanes are so designed 75 as to give a strong blast of air outwardly and upwardly toward a furnace wall, preferably lined with fire bricks 54, thereby having a tendency to cross the course of the fuel thrown off by the nebulizer head. This results in a strong blaze being directed against the furnace wall throughout its entire periphery. The air vanes 44 are supposed to draw hot air downwardly through the openings 42 and direct it outwardly toward 80 the furnace wall to assist the vanes 47 in thoroughly mixing the air and fuel and causing complete combustion. It has been found, however, that the device works quite satisfactorily without the addition of the 85 plate 40 and air vanes 44, but it is believed desirable to make use of this plate in order to prevent dirt from getting into the opening 34 and accumulating on top of the plate 43.

90 Mounted on legs 48 inside of the furnace is a skeleton frame 49 comprising an inner ring 50, outer ring 51 and spokes 52 connecting these rings. The outer ring 51 is provided with an upstanding flange 53 for retaining 100 in position the special fire bricks 54 which cooperate in a peculiar manner with the nebulizer head in producing complete combustion of the fuel. These bricks have upon their inner faces alternate ribs and indentations which catch and direct upwardly the swirling gases thrown outwardly by the nebulizer head and cause the flames to be directed upwardly in close contact with the inner faces of the bricks. While these ribs 105 55 are not essential to the operation of this device, they nevertheless appear to considerably improve its operation. These ribs appear also to reverse the direction of whirl of the agitated gases, thus causing a more 110 intimate mixture of the air and nebulized oil, resulting in an intense blue flame.

A sheet metal plate 56 rests upon the rings 50 and 51 and the spokes 52 and serves as means for supporting the bricks 115 54 and the bottom lining 57, preferably made of asbestos.

An inner ring 58 is shown as supported by means of legs 59 and as having an overlapping joint at 60 with the inner edge of 120 the ring 50. However, by making this joint lap in the opposite direction, the ring 58 can be supported directly by the ring 50 and the posts 59 can be omitted in small sizes of apparatus. At its inner periphery the ring 125 65

58 is provided with an upstanding flange 61 notched at its upper edge as shown at 62. The lower edge of an air collar 63 rests in the notch 62 and the air collar is thereby supported in place. If it is desired to use this device in a smaller sized installation the lower edge of the air collar is thickened to reduce the space between the same and the lower portion of the air vanes 47. Also, the 10 nebulizer head can be quickly removed from the shaft 18 by unscrewing these parts. Another head can then be substituted for the one removed. In this way, the size of the mechanism can be adjusted to the size of installation required by substitution of a minimum number of parts, it not being necessary to change either of the motors, the pump, the valves, any of the electrical equipment, either of the housings, or anything contained therein.

20 In order to adjust the amount of air delivered to the nebulizer head, the vertically adjustable ring 64 is slidably mounted upon the upper end of the bearing housing 20, this ring being provided with a laterally extending flange 65. When the ring is moved upwardly toward the ring 58 the space through which air is admitted to the air ring 63 is reduced, and conversely. Integral with the 30 ring 64 is a socket 66 to which is rigidly secured a shaft or rod 67 provided with teeth 68 which mesh with teeth 69 of an actuating mechanism supported at the side of the casing. The rod 67 passes through a guide lug 35 70 on the side of the casing 20 and also through a correspondingly shaped opening in the bottom flange of the casing 20. This construction serves to guide and rigidly hold the rod 67 against lateral play and to guide the ring 64 in its vertical movements so that there will be no binding between said ring and the housing 20. A shaft 71 carries the pinion which meshes with the rack on rod 67 and extends to the outside of the furnace 40 where a crank 72 is rigidly connected thereto. This shaft passes through a sector 73 which is preferably slotted as shown at 74. Suitable means 75, such as a bolt with a milled or wing nut mounted thereon, serves 45 50 to hold the crank arm 72 in properly adjusted position so that the air regulating means 64, 65 will be held in proper adjustment with relation to the air collar.

55 The shaft 76 of the actuating motor 3 is connected in driving relation with the connecting member 77 which is in turn connected with the core 78 of valve 9. A screw 79 passes through slot 80 in the flange 81 of this connecting member and serves as means 60 65 whereby the connecting member and valve may be adjusted relatively to each other and held in adjusted position. This adjustment is necessary in order to get exactly the proper time relation between the cycles in the 65 functioning of the apparatus. A washer 82

surrounds the end 83 of the core 78 and is pressed against the body of the valve 9 by a nut 84 which is adjusted to a point where the core will fit the body sufficiently tightly to prevent leakage of fuel between the core and body. The flanged nut 85, which serves as a lock nut, is then screwed down against the nut 84 and holds the parts in relatively adjusted position. The flange 86 of core 78^a is provided with a slot corresponding to slot 80 in flange 81, and a screw 79 holds the flanges 85 and 86 in relatively adjusted position so that the two valves will operate in properly timed sequence.

Connected with the pump 11 is inlet pipe 80 90 by means of which the fuel is led to the pump. From the pump the fuel passes through a filter 91 and connection 92 to the manual valve 7, by means of which the flow of fuel to the automatic valve 9 can be controlled. The purpose of the manual valve 8 is to control the flow of gas to the automatic valve 10 as the flow of liquid fuel to the valve 9 is controlled by the valve 7. A bypass pipe 99 carries the excess oil drawn by 90 95 the pump and returns it to the source of supply.

It will be obvious from Figs. 7 and 8 that the entrance and exit ports of the automatic valves are spaced ninety degrees from each other and that the openings into the interior of the cores 78 and 78^a are likewise spaced a distance of ninety degrees, on the surface of the core. These openings communicate through the interior of the core so that when the openings are in registry with the openings in the valve body flow of fluid therethrough may take place. However, through the greater portion of the cycle of rotation of the cores there can be no flow of fluid through the valves. The motor 3 is designed to turn the connector 77 through an arc of one hundred eighty degrees and then discontinue operation. When the current is again supplied to this motor it will turn the connector another one hundred eighty degrees and then stop. The purpose of this is in order to turn the valve cores into position to permit the flow of fluid therethrough and to then turn them into position to stop the flow of the fluid. The complete cycle of operation will be described herein-after.

Through the bottom of the fire box extends an opening 93, arranged substantially in the direction of a plane tangential to a circle drawn about the axis of the shaft 18. This arrangement is chosen in order that the air driven toward the outer wall of the fire box shall not be driven outwardly and downwardly through the opening 93. Extending upwardly to this opening is a gas pipe 94 having a nozzle 95 in proximity to which is a terminal 96 of a high tension circuit one lead of which is shown at 97. This terminal 120 125 130

leads from the high tension mechanism 6 upon the base 1. The other terminal from this high tension apparatus is grounded on the gas pipe. It will therefore appear that 5 when the circuit to the high tension apparatus is closed a spark will be produced between the terminal 96 and the nozzle 95.

Operation

10 While this apparatus is designed to be entirely automatic, it can nevertheless be actuated manually if desired. For the automatic operation thereof, a room thermostat is placed somewhere in the space to be heated and, when the temperature falls to a predetermined adjustable amount, the thermostat will cause the closure of the controlling circuit to the actuating motor 3. This motor then starts running and closes the circuit 15 to the high tension mechanism. Shortly thereafter the shaft of the actuating motor will have caused the opening of the valve 10 which controls the admission of gas to the nozzle 95. This gas is ignited by the 20 sparks passing between the nozzle 95 and the terminal 96. Shortly thereafter, the core of valve 9 will have been turned sufficiently so that oil is admitted through this valve to the chamber 31, passing from thence 25 through the openings 35 and 34 to the dished plate 43. In the meantime, the feed circuit to the high tension apparatus has been opened and that to the driving motor 4 closed, with the result that the nebulizer head starts 30 rotating and the pump begins feeding oil. However, this oil is returned to the source 35 of supply until the valve 9 is gradually opened, whereupon the oil will be slowly and at an increasing rate fed to the rotating nebulizer head. The valve 10 remains open for 40 a short interval of time after the driving motor 4 begins to operate and while the valve 9 is opening. This gives an opportunity for the nebulizer head to produce a combustible mixture in the vicinity of the gas 45 flame issuing from nozzle 95. This combustible mixture is thus ignited and the flame continues even though the gas flame has been extinguished by the closure of valve 50 10 caused by the further rotation of the actuating motor 3. When this motor has completed its cycle of one hundred eighty degrees rotation, it automatically stops and the parts are reset, automatically, for the next 55 part of the complete operation, with the valve 9 in completely open position. This takes place when the room temperature rises to the point at which the thermostat is to function to shut off the heat. When this 60 point is reached, the circuit to the actuating motor is again closed and causes this motor to turn through one hundred eighty degrees, thus closing the oil valve 9 so that no further 65 flow of oil can take place. This operation

also includes the breaking of the circuit to the driving motor 4 which results in stopping the motor, pump and nebulizer head.

It will of course be understood that the specific description of structures and methods set forth above may be departed from without departing from the spirit of my invention. 70

Having now described my invention, I claim:

1. In liquid fuel burning apparatus, a burner head, a vertical, rotary shaft supporting said head and causing rotation thereof, in combination with air driving vanes extending inwardly along the under 80 side of the head from near the periphery thereof and then downwardly along the shaft, and means to regulate the amount of air supplied to the air vanes.

2. In an apparatus of the character described, a slightly dished plate having vanes upon the bottom thereof and projecting downwardly therefrom, a flat cover plate supported adjacent the dished plate but spaced therefrom, said flat plate carrying 90 substantially radial vanes near its outer periphery and between said two plates, said flat plate having perforations therein located inwardly with respect to the last mentioned vanes, and means for supporting and 95 rotating said plates in unison.

3. In an apparatus of the character described, a substantially vertical rotary shaft, a dished plate secured thereto adjacent to the upper end thereof, in combination with 100 a cover plate removably secured to the upper end of the shaft and covering the upper surface of the dished plate, said cover plate having a perforation therein and having air vanes external thereto near the outer 105 periphery of the cover plate, between the dished plate and the cover plate, to cause a secondary circulation of air between the plates, said air vanes having their lower edges spaced slightly from the dished plate, 110 the primary supply of air being furnished from the lower side of the dished plate and the secondary air from between the plates, the circulation of the secondary air preventing 115 the plates from burning out and assisting in the mixing of the air and nebulized oil.

4. In an apparatus of the character described, a substantially vertical rotary shaft, a centrally depressed plate secured directly 120 thereto adjacent the upper end thereof and receiving oil therefrom, said plate fitting the shaft closely so that no air is permitted to pass between the shaft and plate, in combination with a cover plate removably secured directly to the upper end of the shaft and covering the upper surface of the dished plate, said plates being substantially parallel, said cover plate having air vanes near 125 its outer periphery between the two plates, 130

depending from the upper plate and out of contact with the lower plate.

5. In a liquid fuel burning apparatus, a housing, a fire box located above said housing and having an aperture in the bottom thereof over the housing, a plate arranged adjacent the lower end of the aperture and adapted to be moved toward and away from same, a rod rigidly secured to the plate and 10 extending longitudinally of the housing, an adjusting shaft adjacent the housing, operative connection between the shaft and rod, means for rotating the shaft, comprising a lever, and means for holding the rotating 15 means in adjusted position, comprising an adjustable clamp.

In witness whereof, I hereunto subscribe my name to this specification.

HILMER F. RODLER.
